INTERNAL COMBUSTION ENGINE

Hugh M. Rockwell, Freeport, N. Y.

Substitute for application Serial No. 271,725,
April 21, 1928. This application December 20,
1932, Serial No. 648,115

3 Claims. (Cl. 123—30)

This invention relates to improvements in internal combustion engines, and has particular reference to such engines which are adapted for use in aeroplanes, automobiles, and the like.

Internal combustion engines using light hydro-carbon fuels have usually been equipped with carburetors from which the fuel is drawn into the engine cylinders by suction. While a number of commercially available carburetors have been successful from the standpoint of engine efficiency, they have not been entirely reliable and have given rise to objections in aviation work because of their weight. It is therefore one object of this invention to provide novel and simple means for injecting the fuel to the engine cylinders at properly timed intervals in their working cycles.

Another object of the invention is to provide such injecting means which will measure out a definite amount of fuel for each charge, and which makes use of pneumatic pressure to inject fuel into the cylinders.

Another object is to provide an engine with novel crank shaft bearings which will permit slight relative movement between the crank shaft and crank case due to difference in expansion and contraction.

Another object is to provide an engine which will be particularly adapted for use in aeroplanes because of its lightness in weight, simplicity in construction, and dependability.

More specifically the invention contemplates an internal combustion engine with a plurality of cylinders, each operating in a four-stroke cycle, and while the principles may be applied to engines with a greater number of cylinders, it has been specifically illustrated as applied to one having two cylinders in opposed relation, and having pistons connected to a single central crank shaft. Each of the cylinders has a single valve to control admission of air and exhaust of the products of combustion, and associated with the crank shaft is a rotatable fuel measuring member which periodically opens and closes a fluid conduit extending from the head end of one cylinder to the head of the other cylinder. While said fluid conduit is closed, it receives in a recess, a definite amount of gasoline or other hydro-carbon fuel, and as this recess comes into communication with the fluid conduit the gasoline is blown into one of the cylinders by pressure from the other cylinder. In the next revolution, the gasoline is blown into the other cylinder, and so it alternates between the two cylinders. The parts are so arranged and synchronized that as one cylin-

der is drawing in air the other is exploding, and it is the pressure of the successive explosions which effects the fuel injection. In this respect the invention is not restricted since the injection of the fuel may take place at any part of the compression stroke, and can be effected by the transfer of any higher pressure from one cylinder to another. Furthermore, the injection of the fuel by a pump or other mechanical means, instead of by transferred pressure, is also within the contemplation of the invention.

Another feature of the invention is the novel crank shaft and mounting therefor which contributes to the compactness and lightness in weight. This crank shaft has two crank pins 180° apart and disposed between a pair of crank discs which are internally counterweighted. The peripheries of the crank discs constitute the inner races of anti-friction bearings, the outer races of which are secured in the engine crank case in such a manner as to permit expansion and contraction without affecting their alignment. Furthermore, the arrangement of one of the bearings is such as to permit slight relative axial movement between its inner and outer faces, to facilitate assembly and to compensate for slight manufacturing variations as well as differences due to expansion and contraction.

The foregoing and other objects, features, and advantages of the invention will be fully appreciated from the following description in connection with the accompanying drawing, wherein one embodiment is shown by way of illustration, and wherein—

Fig. 1 is a longitudinal sectional view through the improved engine;

Fig. 2 is a detail sectional view on a larger scale through the fuel measuring and injection control means, the section being taken in a plane perpendicular to that of Fig. 1;

Fig. 3 is a fragmentary detail view of the cylinder and fuel conduit connection; and

Fig. 4 is a diagrammatic view of the different cycles of the engine.

This invention was disclosed in my patent application Serial No. 271,725 filed April 21, 1928, of which the present application is a refiling.

Referring particularly to the drawing, it will be seen that the improved engine comprises a crank case 10 and a pair of opposed cylinders 11 and 12, the inner ends of which open to the interior of the crank case, while their outer or head ends are curved and fitted with valves as will later be described. The crank case 10 and cylinders 11 and 12 may be integrally cast as a unit if de-

55

sired, or they may be separately formed as shown and secured together by bolts or the like, the crank cases being composed of an aluminum alloy or other lightweight metal, and the cylinders being 5 of steel or steel-lined aluminum. Pistons 13 of any desired type, are reciprocable in the cylinders 11 and 12, and are fitted with wrist pins 14 for operative connection of pitmans or connecting rods 15 whose inner ends are connected to crank 10 pins 16 of a crank shaft which is rotatable in the crank case 10. The crank pins 16 are shown as being 180° apart, or at opposite sides of the axis of rotation of the crank shaft, and are disposed between two crank discs 17 and 18, which constitute 15 journal portions of the crank shaft. The peripheries of the crank discs are provided with circumferential grooves 19 for the accommodation of steel balls 20, or other rolling anti-friction elements, which are arranged in annular series 20 around the crank discs, and which bear within outer bearing races 21 and 22. The bearing race 21 has a grooved raceway to definitely locate the anti-friction elements 20, while the bearing race 22 has a cylindrical raceway 23 to permit relative 25 axial movement between crank disc 18 and the race 22 whereby to compensate for expansion and contraction of the parts. Said outer races 21 and 22 are further characterized by outwardly extending peripheral flanges 24 and 25, respectively, 30 which are arranged in overlapping relation with annular flanges 26 and 27 in the crank case, and the engaging flanges 24, 26, and 25, 27 are secured together by screws or bolts 28 or other suitable fastening means. With this arrangement 35 the crank case will not be able to expand away from the bearing races in such a manner as to affect their alinement or firm support.

From the foregoing it will be clear that the crank discs constitute bearing races, which, because 40 of their diameters, provide a very substantial support for the crank shaft, and contribute to the desired compactness of the parts. The crank discs are preferably in the nature of relatively thin-walled shells and are internally counterweighted as indicated at 29 to facilitate smooth 45 running of the engine. The crank pins 16 and inner ends of the connecting rods 15 are also provided with anti-friction bearing members 30, whereby to overcome lubrication difficulties and 50 render the engine more dependable in its operation.

When used for aviation purposes, the crank shaft is fitted at one end with a propeller 31 having a stream-line hub and hub cap 32, held in place by bolts or screws 33. The other or rearward end of the crank shaft has a hub 34 rotatable in a fixed sleeve 35, which is provided adjacent the crank disc 18 with a gear 36 meshing with a planetary gear 37 which is carried by said crank disc. A smaller planetary gear 38 is rotatable with the gear 37 and meshes with a driven gear 39 rotatable on the fixed sleeve 35. The proportions of these gears are such that the gear 39 is driven at half as many revolutions per minute as 60 the crank shaft, and secured to or integral with the gear 39 is a cam 40 which is engaged at opposite sides by the inner ends of valve tappets 41. Rotation of the cam 40 causes the tappets 41 to reciprocate, said tappets extending longitudinally behind the cylinders 11 and 12 and being suitably supported by guide members 42 fixed with reference to the cylinders.

The outer end of each valve tappet 41 bears 70 against one end of a rocker arm 43 which is pivoted at 44 at the head end of the corresponding

cylinder and whose other end is intersected by the cylinder axis. Said other end of each rocker arm 43 is provided with a spherical or cylindrical recess 45 on its inner side, for the pivotal connection of one end of a short link 46, the other end of which is similarly connected to the outer end of a stem 47 carried by a poppet valve 48. This valve 48 controls both admission and exhaust of fluid to and from the cylinder in which it is mounted, and as there is only one such valve 10 for each cylinder it can properly be called a master valve. The valve stems 47 are axially guided for reciprocation in bosses 50 on the cylinder heads, and are normally urged outwardly by compression springs 51 to hold the valves 15 in closed positions, and the oscillation of the rocker arms 43 by the tappets 41 effect the alternate opening and closing of the valves. Such movements of the valves are of course synchronized with the movements of the pistons whereby 20 to effect the intake of air, compression, explosion, and exhaust in proper sequence.

It will be observed from Figure 1 that the valves 48 are of relatively large diameter as compared with the bore of the cylinders, thus providing a 25 large valve opening with only a short valve movement. At suitable predetermined intervals in the cycle, fuel is injected into the cylinders through conduits 52 and 53 from any desired type of injection mechanism 54. The fuel is injected into 30 the cylinders at points in or near the head ends thereof, and during either the intake or compression strokes, as desired. In view of the fact that the master valve 48 controls both intake of air and the exhaust of products of combustion, it 35 will be clear that the valve will be kept reasonably cool, and this is important in that it makes possible a higher compression and hence greater power in proportion to cylinder volume. In prior art engines using separate intake and exhaust valves, 40 the exhaust valves have become very hot in operation, whereas in the present structure the incoming air during the intake stroke will help cool the valve after each explosion and exhaust.

In the illustrated embodiment of the fuel injecting means, fluid pressure from one cylinder is utilized to force the fuel into another cylinder. To accomplish this a tubular housing 60 is mounted upon the outer or rear end of the fixed sleeve 35, and rotatably supports a distributor 61 which is connected to the engine crank shaft as at 62 to be driven thereby. This distributor 61 fits snugly in a central bore of the housing 60, and is provided with a recess 63 which is adapted to periodically effect communication between divergent 55 ports 64 and 65. The conduits 52 and 53 are respectively connected with the ports 64 and 65, and the arrangement is such that during the greater part of the cycle, the ports are cut off from each other by the periphery of the distributor 61. At 60 one side, preferably the top, the housing 60 is provided with a boss which is centrally apertured to intersect the housing bore, and which is connected to a gasoline supply tank from which the fuel is fed by gravity to the supply port 66.

As the distributor rotates, the recess 63 becomes filled with the fuel while it passes the supply port 66, and it carries this fuel around to the point where it communicates with the transfer passages or ports 64 and 65. At this time, one 70 of the cylinders has a higher pressure than the other, and as a result the fuel in the recess 63 will be blown into the cylinder having the lower internal pressure. In the next revolution the pneumatic draft will flow in the opposite direction, and 75

so the injection of the fuel will alternate from one cylinder to the other. In the use of light liquid fuels such as gasoline, the fuel will be vaporized by the heat as it enters the cylinders and so a good mixture is easily produced.

In order to vary the speed of the engine, the cam 48 is tapered, and is longitudinally adjustable by a screw-threaded rod 78, which can be manually rotated to shift a finger 71 engaging a peripheral groove 72 in the cam. This adjustment varies the stroke of the valve tappets, and thus increases or decreases the valve openings. The variation in speed of rotation can also be effected by varying the amount of fuel injected, for example, by the use of needle valves 13 and 14 mounted in conjunction with the transfer ports 64 and 65, said needle valves being movable by cams 15 and 16 which are geared to the control rod 78. Of course, other specific adjusting means may be provided as will be obvious to those skilled in the art, and the fuel injected during each cycle will always be of a definitely measured quantity.

The novel fuel injection means is illustrated diagrammatically in Fig. 4, and as has been previously stated, it can be applied to engines with more than two cylinders, regardless of whether the cylinders are opposed or in line, or in any other relation. It is to be noted that in practice the transfer ports 64 and 65 are opened simultaneously by the distributor recess 63 as shown in Fig. 2, this structural feature being slightly different in the diagrammatic showing of Fig. 4. Furthermore, the method and apparatus for transferring the fuel by the pressure in the combustion chamber of one cylinder to the combustion chamber of another cylinder, with the master valve for air intake and exhaust, may be applied to high compression engines if desired.

The improved engine is of extremely simple construction and light weight, and will be strong and durable in service. The invention is suscep-

tible of numerous modifications other than those mentioned, and the right is herein reserved to make such changes as fall within the scope of the appended claims without departing from the spirit of the invention.

5

Having thus described my invention, what I claim is:

1. In an internal combustion engine, a pair of cylinders fitted with reciprocable pistons, a crank shaft to which both of the pistons are connected, a single valve in each cylinder for controlling the admission of air and the exhaust of products of combustion, a fuel measuring device operable with the crank shaft, and means for injecting fuel to the cylinders from said measuring device by fluid pressure during their air intake stroke.

2. In an internal combustion engine, a pair of cylinders, a crank shaft, pistons reciprocable in the cylinders and connected to said crank shaft, a single valve in each cylinder for controlling the admission of air and the exhaust products of combustion, fuel measuring means associated with the crank shaft, and fuel injecting means utilizing air from the compression stroke of one cylinder to force liquid fuel into the other cylinder during the air intake stroke thereof.

3. In an internal combustion engine, a plurality of cylinders, pistons operable therein, a crank shaft to which the pistons are connected, fluid conducting means extending from the head end of one cylinder to the head end of another cylinder, a fuel measuring device adapted alternately to open and to close communication through said fluid conducting means and to present definitely measured charges of fuel thereto, and means for actuating said fuel measuring device at definite points in the piston cycles, and adjusting means for varying the flow of fluid through said fluid conducting means whereby to control the speed of rotation of the crank shaft.
